(57) **CLAIM**

The ornamental design for a shoe insole, as shown and described.

DESCRIPTION

FIG. 1 is a front view of a shoe insole showing my new design; FIG. 2 is a rear view thereof; FIG. 3 is a top view thereof; FIG. 4 is a bottom view thereof; FIG. 5 is a right view thereof; FIG. 6 is a left view thereof; FIG. 7 is a front perspective view thereof; FIG. 8 is a rear perspective view thereof; FIG. 9 is an exploded perspective view thereof; FIG. 10 is a perspective view thereof shown in a used condition; and, FIG. 11 is a cross sectional view taken along lines 11-11 of FIG. 1. The broken lines shown in the drawings represent portions of the shoe insole that form no part of the claimed design.

1 Claim, 6 Drawing Sheets
